UNITED STATES PATENT OFFICE.

WILLIAM R. AIMES, OF ATCHISON, KANSAS.

ADVERTISING DISPLAY APPARATUS.

1,368,533.

Specification of Letters Patent. Patented Feb. 15, 1921.

Application filed November 17, 1919. Serial No. 338,707.

To all whom it may concern:

Be it known that I, WILLIAM R. AIMES, a citizen of the United States, residing at Atchison, in the county of Atchison and 5 State of Kansas, have invented certain new and useful Improvements in Advertising Display Apparatus, of which the following is a specification.

This invention relates to an apparatus for 10 displaying advertisements, such as designs, samples of various articles or goods, photographs or analogous materials, and an object of the invention is to provide in a display apparatus of this type means for successively displaying a plurality of separate 15 advertisement carrying boards or curtains, behind a transparent panel or window in a cabinet of the display apparatus, thereby permitting the individual displaying successively, of a large number of advertisements 20 in a relatively small space, and also lending attractiveness to the display apparatus by the constant changing of the matter displayed.

25 The present invention relates to an advertising display apparatus of the type illustrated in the application filed July 31, 1919, Serial No. 314,548, an object of the present invention being to provide a display 30 apparatus of this type which is relatively simple in construction and provides a plurality of guides, for guiding the movement of the advertising board carrying chains, for preventing them from accidentally being 35 coming disconnected with guiding and drive sprockets and also to maintain uniform non-oscillating movement of the display or advertising board.

Another object of the invention is to provide 40 in a display apparatus as specified a chain structure carrying a plurality of pick up members which are spaced at predetermined distances along the chain, and are adapted to engage the carrying rods of the 45 sign boards, for moving them from exhibiting positions into non-exhibiting positions, and for providing means simple in construction for releasing the display boards from the pick up or carrier members of the chain 50 and depositing them upon an inclined guide structure over which they pass into an exhibiting position.

Other objects of the invention will appear 55 in the following detailed description taken in connection with the accompanying draw-

ing, forming a part of this specification, and in which drawing:

Figure 1 is a vertical section through the improved display apparatus.

Fig. 2 is a vertical section through the display apparatus taken at right angles to the section illustrated in Fig. 1.

Fig. 3 is a detail view partly in section and partly in elevation of the advertising device illustrating one of the carrier or pick up members and its manner of engaging the display board carrying rod.

Fig. 4 is a cross section on the line 4—4 of Fig. 3.

Fig. 5 is a side elevation of one of the carrier members illustrating the manner of engagement with the display board carrying rods, and

Fig. 6 is a fragmentary enlarged section through the display apparatus illustrating the manner in which the display boards are fed into an exhibiting position and moved therefrom by the carrying chains.

Referring more particularly to the drawings, wherein like characters indicate like 80 and corresponding parts throughout the several views, the improved display apparatus includes a cabinet 10 provided with a transparent panel or window 11 in the front side thereof, behind which the display boards 85 12 are positioned, for displaying the advertising matter thereon.

The display boards 12 are carried by supporting rods 13, and these rods have guiding rollers 14 mounted thereon, the peripheries of which are concaved for fitting over the supporting guiding rails 15 of the rack structure 16. The rack structure 16 inclines downwardly from the rear wall of the housing or casing 10 toward the front wall thereof, to cause the display boards 12 to feed by gravity downwardly thereover for positioning behind the window 11, as clearly shown in Fig. 1 of the drawings. The display boards 12 are moved, from behind the window 11, by endless chains 15', which travel about drive sprockets 16^a mounted upon a drive shaft 17, and about a plurality of guiding sprockets 18, which are mounted in the upper corners of the casing 10, as clearly shown in Fig. 1 of the drawings. These endless chains 15' each have carrier or pick up members 19 attached thereto, at spaced intervals. The pick up members or carriers 19 are pivotally mounted upon ex- 110

tended pins 20 which make up a part of the chain structure, and the lower ends of these carriers are weighted so as to maintain the carriers in a vertical position at all times, 5 having their socketed ends upwardly. These upper socketed ends are provided with recesses or sockets 21 which receive therein the ends of the board carrying rods 13, and the sides of the upper ends of the carriers 10 facing the chains 15' are recessed to a greater extent than the recesses 21 as shown at 22, for receiving therein the heads 23 which are formed upon the ends of the rods 13 to prevent lateral displacement of the 15 rods 13 relative to the carriers, during movement of the rods and the boards carried thereby, under action of the chains 15'.

Suitable stops 24 are carried by the inner surface of the front side of the cabinet or 20 housing 10 and they are provided with concaved surfaces 25 shaped to fit the periphery of the guiding rollers 14, so that when the foremost display board upon the rack structure 15 moves forwardly, as the preceding 25 display board is moved out of display position, the guide rollers 14 will be engaged against the concaved surfaces 25 of the stops 24, and held in proper displaying position behind the window 11 and also in position to 30 be picked up by the next carrier 19 which approaches it during the travel of the chains 15'. The carriers 19 approaching the rod 13 of the display board 12 which is in position behind the window 11, will receive the rod 35 13 in the recesses 21 thereof at the heads 23 of the rods in the recesses 22, lifting the rod 13 upwardly with the upward travel of the chain 15' and consequently moving the display board 12 upwardly from behind the 40 window 11 until the rod 13 and carrier 19 reaches the forward guide sprockets 18 where their direction of movement will be transferred to a substantially horizontal path across the upper end of the cabinet 10 45 until they reach the rearmost guide sprockets 18 where their direction of movement will again be diverted, and they will be carried downwardly in the rear end of the cabinet until the guide rollers 14 are engaged 50 upon the convex surface 27 of the cam block 28 which will force the rods 13 out of the sockets in the carrier members 19, and owing to the convexed faces 27 deliver the rod 13 and its board 12 to the rack structure 55 16 over which it will move downwardly until it engages the rearmost display board structure carried by the rack and it will eventually be fed, by gravity into an exhibiting position behind the window 11, 60 from which it will be again moved by the chains 15'.

Guiding pipes 29 are provided, for guiding the movement of the chains 15' so as to prevent these chains from slipping off their 65 sprockets or vibrating unnecessarily during

operation of the device. The ends of the guiding pipes 29 are preferably flared, as shown at 30 and they are provided with longitudinally extending slots 31, which permit the projection of the pins 20 therethrough. 70 Substantially concavo-convex guide disks 33 are mounted upon the pins 20, with their convexed surfaces outwardly from the chains 15', and these washers will engage the inner surfaces of the pipes 29 to properly center the chains 15' therein and in case the chains are not properly alined with the pipes, upon the movement of the respective carriers to the inlet ends of the chains, the convexed surface of the guide disks 33 engaging the flared mouths 30 will guide the chains into their proper positions and engaging the inner surfaces of the pipes during the travel of the chains therethrough, 75 will maintain the chains in centered position 80 within the pipe.

The driving shaft 17 may be operated by any suitable type of prime mover, such as an electric motor illustrated at 40 in Figs. 1 and 2 of the drawings, the main drive shaft 90 41 of which is connected by means of a sprocket and chain transmission mechanism 42 with a relatively short shaft 43, which is in turn connected by means of a sprocket and chain transmission 44, with the shaft 17, 95 for operating the same.

Changes in details may be made without departing from the spirit of this invention, but;

I claim:

1. In an advertising display apparatus, the combination, of a cabinet, provided with a display window, a supporting rack therein inclining toward said window, a plurality of display boards, supported by said rack and adapted to be moved under gravity action into displaying position behind said window, endless chains movable within said cabinet, carriers pivotally mounted upon said chains at spaced intervals and adapted to engage the display boards and move them out of displaying positions, stop members carried by said cabinet and adapted to hold said boards in displaying position behind the window and in position for engagement by 105 said chain carried carriers, and tubular guides for receiving said chains to prevent accidental lateral movement of the chain.

2. In an advertising display apparatus, the combination, of a cabinet, provided with a display window, a supporting rack therein inclining toward said window, a plurality of display boards, supported by said rack and adapted to be moved under gravity action into displaying position behind said window, endless chains movable within said cabinet, carriers pivotally mounted upon said chains at spaced intervals and adapted to engage the display boards and move them out of displaying positions, stop members 115 120 125 130

- carried by said cabinet and adapted to hold said boards in displaying position behind the window and in position for engagement by receiving said chain carried carriers, 5 and tubular guides for said chains to prevent accidental lateral movement of the chain, and means carried by said cabinet for lifting the boards from said carriers and delivering the boards to said racks.
- 10 3. In an advertising display apparatus, the combination, of a cabinet, provided with a display window, a supporting rack therein, inclining toward said window, a plurality of display boards supported by said 15 rack and adapted to be moved under gravity action into displaying position behind said window, endless chains movable within said cabinet, carriers pivotally mounted upon said chains at spaced intervals and adapted 20 to engage the display boards and move them out of displaying positions, stop members carried by said cabinet and adapted to hold said boards in displaying position behind the window and in position for engagement 25 by said chain carried carriers, tubular guides for receiving said chains to prevent accidental lateral movement of the chains, means carried by said cabinet for lifting the boards from said carriers and delivering the 30 boards to said racks, and means carried by said chains for engagement with said tubular guides to properly position the chains within the guides.
4. In an advertising display apparatus, the combination of a plurality of display boards adapted to be moved under gravity action into displaying positions, endless chains, carriers pivotally carried by said endless chains at spaced intervals, said carriers 40 adapted to move said display boards out of displaying positions, tubular guides for receiving said endless chains, and substantially concavo-convex guide disks carried by said chains and presenting convexed surfaces 45 for engagement with the interior of said tubular guides to properly center the chains within the guides.
5. In an advertising display apparatus, the combination of a plurality of display 50 boards adapted to be moved under gravity action into displaying positions, endless chains, carriers pivotally carried by said endless chains at spaced intervals, said carriers adapted to move said display boards out 55 of displaying positions, tubular guides for receiving said endless chains, substantially concavo-convex guide disks carried by said chains and presenting convexed surfaces for engagement with the interior of said tubular 60 guides to properly center the chains within the guides, and cam members for removing said boards from said carriers.
6. In an advertising display apparatus, the combination of a cabinet provided with a 65 displaying window, a rack, in said cabinet and inclining toward said displaying window, rails upon said rack, a plurality of display boards, rollers carried by said display boards and riding upon said rack, whereby the display boards will move under gravity 70 action into display position behind said window, stop members carried by said cabinet for engaging said rollers to support said boards in display position and partly in advance of said rack, and means for moving 75 said boards out of displaying positions.
7. In an advertising display apparatus, the combination of a cabinet provided with a displaying window, a rack in said cabinet and inclining toward said displaying window, rails upon said rack, a plurality of display boards, rollers carried by said display boards and riding upon said rack whereby the display boards will move under gravity 80 action into displaying position behind said window, stop members carried by said cabinet for engaging said rollers to support said boards in display position and partly in advance of said rack, means for moving 85 said boards out of displaying position, cam 90 members carried within said cabinet and adapted to engage said rollers for releasing them from said last named means and delivering them to said rack.
8. In an advertising display apparatus, the combination of a cabinet provided with a displaying window, a rack in said cabinet and inclining toward said displaying window, a plurality of display boards, rods attached to the upper end of said display 100 boards, rollers mounted upon said rods and engaging said rails whereby the display boards will be set under gravity action into display position behind said window, heads upon the ends of said rods and means for engaging said heads and rods for moving the 105 display boards out of display position.
9. In an advertising display apparatus, the combination of a cabinet, a display window in said cabinet, a rack in said cabinet 110 inclining toward said display window, a plurality of rods, display boards carried by said rods and adapted to be supported by said racks for movement thereover under gravity action into display position behind said window, heads upon the ends of said rods, endless chains movable within said cabinet, and carriers pivotally carried by said endless chains at spaced intervals and adapted to engage the heads on said rods to move said 115 display boards out of displaying position.
10. In an advertising display apparatus, the combination of a cabinet, a display window in said cabinet, a rack in said cabinet inclining toward said display window, a 120 plurality of rods, display boards carried by said rods and adapted to be supported by said racks for movement thereover under gravity action into display position behind said window, heads upon the ends of said 125 rods.

- rods, endless chains movable within said cabinet, carriers pivotally carried by said endless chains at spaced intervals and adapted to engage the heads and said rods 5 to move said display boards out of displaying position, and cam members carried within said housing for moving said rods out of said carriers and delivering them to said racks.
- 10 11. In an advertising display apparatus, the combination of a cabinet, a display window in said cabinet, a rack in said cabinet inclining toward said display window, a plurality of rods, display boards carried by 15 said rods and adapted to be supported by said racks for movement thereover under gravity action into display position behind said window, heads upon the ends of said rods, endless chains movable within said 20 cabinet, carriers pivotally carried by said endless chains at spaced intervals and adapted to engage the heads and said rods to move said display boards out of displaying position, cam members carried within 25 said housing for moving said rods out of said carriers and delivering them to said racks, and stop blocks carried within said window for supporting said display boards in displaying position partly in advance of 30 said rack behind said cabinet and in position to be engaged by said chain carried carriers.
12. In an advertising display apparatus, the combination of a cabinet, a display window in said cabinet, a rack in said cabinet 35 inclined toward said display window, a plurality of rods, display boards carried by said rods, rollers arranged to engage said racks carried by said rods, the boards being adapted to be supported by said rollers for 40 moving over said rack under gravity action into displaying position behind said window, heads upon the ends of said rods, endless chains movable within said cabinet, carriers pivotally carried by the endless chains at spaced intervals adapted to engage the 45 heads and said rods to move said display boards out of displaying position, cam members arranged within said cabinet directly in rear of said rack for raising and moving said rods forwardly on to said rack and off 50 of said carriers, and concave stop blocks arranged within the cabinets directly in front of said rack for supporting said display boards partly in advance of said rack in displaying position behind said window and in 55 position to be engaged by said chain carried carriers.
13. In an advertising display apparatus, the combination of a cabinet, a display window in said cabinet, a rack in said cabinet 60 inclining toward said display window, a plurality of rods, display boards carried by said rods and adapted to be supported by said racks for movement thereover under gravity action into display position behind 65 said window, enlarged heads upon the terminals of said rods, endless chains movable within said cabinet, carriers pivotally secured to said chains at spaced intervals, the upper ends of said carriers being recessed 70 to receive the rods, the inner faces of said carriers at the upper end thereof being cut out to receive said heads, the lower ends of said carriers being weighted, so as to normally hold the same in a vertical position, 75 means arranged within the cabinet for moving said rods from off of said carriers and delivering them to said rack, and stop blocks carried by the cabinet for supporting said display board in displaying position.

WILLIAM R. AIMES.
